FUEL AND WATER FEEDING AND STEAM
DISCHARGE ARRANGEMENT FOR COM-
BUSTION CHAMBERS

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application February 7, 1948, Serial No. 7,015

3 Claims. (Cl. 60—46)

1

This invention relates to combustion chambers as used in rockets and other propulsion apparatus.

It is an important object of the invention to provide a combustion chamber wall of improved construction and of increased strength, and one which is well adapted to be effectively cooled by the combustion elements introduced therethrough.

A more specific object is to provide a combustion chamber wall of rigid metallic construction and having impervious inner and outer surface portions and an intermediate porous portion, and all preferably of a single metal or alloy.

Another feature of the invention relates to improved means for producing steam in such a combustion chamber and for discharging steam therefrom.

The invention further relates to arrangements and combinations of parts which will be hereinafter set forth and more particularly pointed out in the appended claims.

Preferred forms of the invention are shown in the drawing, in which

Fig. 1 is a sectional side elevation of a combustion chamber embodying this invention;

Fig. 2 is a detail sectional end elevation, taken along the line 2—2 in Fig. 1;

Fig. 3 is a sectional end elevation on a reduced scale and taken along the line 3—3 in Fig. 1;

Figs. 4 and 5 are enlarged sectional side elevations of certain portions of Fig. 1; and

Fig. 6 is a sectional side elevation of a modified construction.

Referring to Figs. 1 to 5, a combustion chamber C is shown, having opposed conical walls 10 and 11 and provided with a conical discharge nozzle N. Outer walls or casings 12 and 14 provide jacket spaces S and S' to which combustion liquids may be supplied under pressure through feed pipes 16 and 17. Feed openings or slots 20 and 21 are provided in the adjacent end portions of the conical walls 10 and 11.

One combustion liquid, as gasoline, may be supplied through the pipe 16 to the space S and will be projected into the chamber C in the form of flat sprays. A second combustion liquid, as liquid oxygen, may be similarly supplied under pressure through the pipe 17 to the space S' and will be sprayed through the openings 21. These sprays intersect and are intimately intermingled as indicated in Fig. 1, and may be ignited by an axially disposed igniter 23 which may be of the hot flash or any other convenient type.

An important feature of the invention relates

2

to the filling of the jacket spaces S and S' with porous metallic materials M and M' which are of rigid construction but which also provide continuous filamentary ducts through which the combustion liquids can flow relatively freely.

Preferably the walls 10 and 11, casings 12 and 14, and filling materials M and M' are all composed of the same metal or alloy and are so united that they form in effect single integral metallic structures.

This unitary construction may be conveniently achieved by filling the spaces S and S' with compressed and finely divided metal fragments or metal powder and by thereafter sintering or partially softening and melting the metal fragment to cause them to adhere to each other and to the enclosing metal walls. The metal should have good heat conductivity. A mixture of silver and tungsten may be used to advantage, also a mixture of copper and tungsten.

The porous filling materials M and M' are stopped off to provide clear spaces adjacent the feed pipes 16 and 17 and adjacent the feed opening or slots 20 and 21.

It is sometimes desirable to generate steam by a portion of the heat developed in the combustion chamber C.

For this purpose, the adjacent ends of the conical chamber walls 10 and 11 are spaced apart to admit a band 30 having a plurality of small feed openings 31 which communicate with an inner volute 32 (Figs. 1 and 2) to which water under pressure is fed through a pipe 33.

An outer volute 35 surrounds the inner volute 32 and is provided with a plurality of tubes 36 which connect into the combustion chamber C through ports 37. The outer volute 35 has a discharge pipe 40 through which steam may be delivered, to be used for any other useful purpose.

With this construction, water will be sprayed into the combustion chamber through the relatively small feed openings 31 from the inner volute 32 and will be quickly changed into steam by the hot combustion gases in the chamber C. This steam, with some small admixture of combustion gases, then escapes through the ports 37 and tubes 36 to the volute 35, and to be thereafter discharged through the pipe 40.

Effective provision is thus made for feeding the combustion liquids under pressure without requiring external power, which is of substantial importance in the operation of rocket apparatus.

A slightly modified construction is shown in Fig. 6, in which the combustion chamber C' has approximately semi-spherical end walls 50 and 51.

and is provided with the usual nozzle N'. Outer casings 52 and 53 enclose jacket spaces S2 and S3, the middle portions of which are filled with metallic material M2 and M3. One combustion liquid is fed to the space S2 under pressure through a feed pipe 55 and the other combustion liquid is fed to the space S3 through a feed pipe 56.

Feed openings 60 and 61 are provided in conical end portions 62 and 63 of the chamber walls 50 and 51, so that the sprays of liquid intersect at substantial angles as in the form previously described. Any usual igniter 65 may be provided for the chamber C'.

The integral construction of the chamber walls, jacket casings and metal filling materials will be as previously described in connection with Fig. 1, and the use and advantages of this construction are the same.

It is noted, however, that the substantially spherical shape of the combustion chamber C' gives maximum volume for a given weight of chamber wall and casing and also give exceptional strength.

Having thus described the invention and the advantages thereof, it will be understood that the invention is not to be limited to the details herein disclosed, otherwise than as set forth in the claims, but what is claimed is:

1. In combustion apparatus, a combustion chamber having reversed conical end walls, means to spray two different combustion liquids to said chamber at points adjacent the greatest chamber diameter, a volute encircling said chamber at said greatest diameter and having spray openings into said chamber, means to feed water to

said volute, an outer volute having tubular connections through said first volute to steam ports in the wall of said combustion chamber, and means to discharge steam from said outer volute.

5 2. The combination in combustion apparatus as set forth in claim 1, in which the tubular connections are curved in a diametral plane of said chamber to induce rotational circulation of the steam in said outer volute.

10 3. In combustion apparatus, a combustion chamber having reversed jacketed conical end walls, means to feed two different combustion liquids through said jacketed walls to said chamber at points adjacent the greatest chamber diameter, a volute interposed between said jacketed end walls and encircling said chamber at said greatest diameter and having spray openings into said chamber, means to feed water to said volute, an outer volute having tubular connections extending through said first volute to steam ports in the wall of said combustion chamber between said water spray openings, and means to discharge steam from said outer volute.

25 ESTHER C. GODDARD,
25 *Executrix of the Last Will and Testament of Robert H. Goddard, Deceased.*
